UNITED STATES PATENT OFFICE.

CHARLES BOOZ, OF BUFFALO, NEW YORK, ASSIGNOR TO HENRY M. BIRGE,
OF SAME PLACE.

DESIGN FOR WALL-PAPER.

SPECIFICATION forming part of Design No. 26,142, dated September 29, 1896.

Application filed August 24, 1896. Serial No. 603,801. Term of patent 31 years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

10 The design consists of a series of ornaments of the Empire style of design, composed of an ornamental wreath and an eagle, with open wings in the center and placed at regular distance apart upon a background of wide vertical stripes, as represented in the accompanying drawing.

15 The border for the said design is formed of similar ornaments of the Empire style of design placed in the center of large circles, with 20 ornamental figures and a grotesque figure of

a winged horse on each side of said ornaments and connected by an ornamental festoon, as shown. Small ornaments are arranged at the top and bottom of said circles and ornamental scrolls diverge right and left from the small 25 ornaments below the circles, as shown. An ornamental band forms the bottom of the border, as shown.

What I claim is—

1. The design for wall-paper herein shown 30 and described.
2. In the design for wall-paper the border herein shown and described.

Witness my hand this 10th day of August, 1896.

CHARLES BOOZ.
